UNITED STATES PATENT OFFICE.

EINAR TROYE AND EMIL EDWIN, OF CHRISTIANIA, NORWAY, ASSIGNORS TO NORSK HYDRO-ELEKTRISK KVAELSTOFAKTIESELSKAB, OF CHRISTIANIA, NORWAY.

ELECTRIC-ARC-FURNACE PLANT.

1,122,555.

Specification of Letters Patent. Patented Dec. 29, 1914.

Application filed June 26, 1914. Serial No. 847,510.

To all whom it may concern:

Be it known that we, EINAR TROYE and EMIL EDWIN, subjects of the King of Norway, both residing at Christiania, Norway, 5 have invented certain new and useful Improvements in Electric-Arc-Furnace Plants; and we do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to electric furnace plants of the kind, where the power is utilized for several arcs in a multiphase system, for example several arcs or furnaces of the Birkeland type.

20 By the transmission of power to plants with arc furnaces it is very important, that the furnaces have the connection affording the greatest stability because it is in this way that the best security of service and 25 earning capacity is attained, while at the same time the necessary transforming of tension may be carried out with the best possible economy and with the simplest possible apparatuses. Both these objects are at-

30 tained by the present invention, which is the result of extensive experiments and theoretical researches, and which will be best understood by means of the following considerations: It is known that in any electric sys-

35 tem all changes will be counter-acted by forces, which are created by the change itself. When it is considered therefore, that the stability of an electric arc is due to the forces which counter-act the sudden changes

40 which are produced in the arc current by means of exterior influences it will be evident that with regard to the first harmonic of the current it is important to place the whole of the electric system obtained by the

45 connection in such relation of dependence that all links of the system are utilized for the stabilizing of every separate link viz. that the current in each arc contributes to the stabilizing of all the other arcs in the

50 system. The current curve of the arc approaches always to a certain degree the sinusoid, and all the higher harmonics in the tension curve will therefore be idle. As these will accordingly lessen the total power

55 factor, it is important to limit them as far as

possible and then to localize them so that their effect on the circuit or mains will be the smallest possible. For this reason and at the same time because they contribute probably to a very great extent to the interior stability of the arc the higher tension-harmonics should be localized to the arc to which they belong and be prevented from being transmitted to the electric circuit.

The above considerations which have not 60 yet to the knowledge of the applicants been taken up in literature make the foundations for the connections forming the present invention.

The objects of this invention with respect 70 to the connection of the arcs are: To put the several links in depending connection with regard to the first harmonic of the current and make them independent of each other with regard to the higher harmonics of tension. Now it appears that with regard to the connection of the arcs, the symmetrical multiphase system with star connection with or without a neutral capable of being switched off satisfies best the requirements 75 80 with regard to the current, as

$$\Sigma i=0,$$

the several links therefore being in direct dependence of each other. The second requirement with regard to the tension must 85 therefore be satisfied within the scope of this connection, and this can not only be obtained by means of a choking transformer (hedgehog transformer), but also by means 90 of choking coils generally, whereby the connection described in the following is obtained: By the use of a choking transformer one has also the advantage, that if the conditions require a higher main tension, the 95 necessary transforming down of this tension may be performed by the choking transformers. As a result of the large units (1000 kw. and more) used in the industries connected with the processes referred to, it 100 will be possible to build the choking transformers economically for very high primary tensions and ratios, for instance from 100000 volt-5000 volt. The choking transformer and its connection may evidently be 105 adapted for single or multiphase system, and it is also possible to use Scotts connections, etc.

In the accompanying drawings, in which like parts are similarly designated—Figure 110

1 is a diagram showing a Birkeland furnace in each phase connection of a three phase transformer and connected to a neutral wire. Fig. 2 is another diagram, in which the furnaces are in induction circuits. Fig. 2^a is a modification of Fig. 2, where a plurality of furnaces are supplied with induced current from the same primary winding or coil. Fig. 3 is a diagram illustrating the use of choking coils.

- 10 In a three-phase system the connection may be carried out, so that the furnaces, viz. the arcs are connected in mesh. However according to the above considerations 15 the connections as shown on Figs. 1, 2 and 3 on the accompanying drawing in connection or not with a neutral would be the most advantageous system not only with regard to the stability but also with regard 20 to regulating, security of service, and in this case also with regard to the transforming. It is evident from the above, that in the following examples the word furnace may 25 also be adapted to one or more arcs in a furnace, so that the system may be used as well for the connection for instance of three furnaces, each having one or more arcs, as for the connection of three arcs within the same furnace.
- 30 It should be noted, that the diagrams have been made as simple as possible, but that also connection in parallel may be used. Also in Diagram 2 the furnaces or the arcs may be connected as shown on Fig. 2^a, where 35 for each transformer one may have two or more furnaces or arcs.

40 The three phase system affords certain advantages technically, while the multiphase system affords the advantage that a change in one of the several links of the system causes a comparatively smaller retroaction on the total system, so that the stabilizing will be better. For simplicity's sake the accompanying diagrams are carried out as three-phase systems.

45 On Fig. 1 *a* is a three phase choking transformer and *b* are the furnaces or the arcs of the Birkeland type, which are connected in star, having also a neutral point in the 50 choking transformer. The primary coil of the choking transformer may be connected in mesh or in star according to the conditions. In this condition the independence of the higher harmonics of tension are attained thereby that the high reactance of 55 the choking transformer prevents the oscillations of tension created in each link from penetrating to the other furnaces connected to the system, while it is evident that dependence in the first harmonic of the current 60 may also be attained. The same object is attained in Fig. 2, where the three-phase choking transformer is divided into three single phase choking transformers *c*. By 65 this connection the neutral is formed by a

special transformer *o*, which may be constructed with or without increased induction.

In Fig. 3 the connecting conditions for the arcs have been attained without choking 70 transformers by means of choking coils, the requirements for the current being obtained as before, while the requirements for the tension are attained by inclosing the oscillations of tension between parts of the reactance necessary for stabilizing and limiting them to the arc itself. The furnaces or the arcs are indicated by *b* as before, while *c* indicates parts of the stabilizing reactance. This system of connection may also 75 be useful in other furnace connections as it lessens the danger of a puncture in the furnace. "Choking coil" here indicates any kind of reactance.

80 By the connection shown it is not possible in all conditions to start the furnaces without a connection between the star point of the furnace and the neutral of the system. The former therefore should be capable of being switched off and should be so adjusted, 85 that when the neutral is in connection it is tried as far as possible to obtain the best 90 conditions in accordance with the above considerations, viz. dependence regarding the first harmonic of the several currents. In 95 other words the neutral must in this case be carried out with an increased reactance or other adjustable resistance. Under certain conditions the neutral may and should 100 be connected to earth.

Claims:

1. In a multiphase furnace system comprising a plurality of arcs in combination with an electric circuit including said arcs; means to transform the tension supplied to said arcs, a reactance in said circuit, a neutral point in mains of said circuit, and an electrical connection between said neutral point and the star points of the furnace system. 105
2. Means for stabilizing a plurality of arcs comprising a multiphase circuit including said arcs, means to supply multiphase current to said circuit, reactance in said circuit tuned to pass only the first harmonic 110 of the current, and a neutral electric return connection common to all the arcs. 115
3. Means for stabilizing a plurality of arcs comprising a multiphase circuit including said arcs, means to supply multiphase current to said circuit, said circuit having reactance tuned to pass on the first current harmonic of each arc, a grounded neutral metallic return connection and means in said connection between the arcs and the supply means for said arcs to interrupt the neutral metallic return, whereby the arcs become interdependent with respect to the first harmonic only. 120
4. Means for stabilizing a plurality of 125

arcs comprising a multiphase circuit, a multiphase transformer in said circuit, an arc in each phase connection to said transformer, and a neutral connection between 5 the neutral point of the transformer and the star points of the arc.

5. Means for stabilizing a plurality of arcs comprising a multiphase circuit, an arc for each phase connection of said circuit, 10 and each phase connection having reactance tuned to pass only the first harmonic of the current, a transformer connected to said circuit and a metallic neutral connection common to all the phase connections and connected to the neutral point of the 15 transformer.

6. Means for stabilizing a plurality of arcs comprising a multiphase circuit, an arc for each phase connection of said circuit, 20 and each phase connection having reactance turned to pass only the first harmonic of the current, a transformer connected to said circuit and a grounded metallic neutral connection common to all the phase connections 25 and connected to the neutral point of the transformer.

7. Means for stabilizing a plurality of arcs comprising a multiphase circuit, an arc for each phase connection of said circuit, 30 and each phase connection having reactance

tuned to pass only the first harmonic of the current, a transformer connected to said circuit and a metallic neutral connection common to all the phase connections and connected to the neutral point of the transformer, 35 and a switch in said metallic connection whereby the neutral point of the furnaces may be made independent of the neutral point for the phase connections.

8. Means for stabilizing a plurality of 40 arcs comprising a multiphase star circuit, each phase connection supplying an arc, reactance means in each connection in which the arcs are interposed in series said means tuned to pass only the first harmonic of the 45 current, a grounded neutral metallic connection common to said phase connections and the neutral point for said phase connections, and a switch in said metallic connections between said arcs and said neutral 50 point.

In testimony that we claim the foregoing as our invention, we have signed our names in presence of two subscribing witnesses.
